(57) **CLAIM**

The ornamental design for a venting plug for a container, as shown and described.

DESCRIPTION

FIG. 1 is a bottom perspective view of the venting plug for a container showing the new design;

FIG. 2 is a side view thereof;

FIG. 3 is a top plan view thereof;

FIG. 4 is a top perspective view thereof;

FIG. 5 is an exploded view thereof; and,

FIG. 6 is an exploded perspective view from below showing the bottom cover separated from the venting plug and flipped over for clarity of disclosure.

In the drawings, the broken lines showing portions of a venting plug for a container depict environment and form no part of the claim.
